DESIGN FOR A BUGGY.

JOHN REYNOLDS, OF WASHINGTON, DISTRICT OF COLUMBIA.

Design No. 2,529, dated December 11, 1866.

The Schedule referred to in these Letters Patent and making part of the same.

TO ALL WHOM IT MAY CONCERN:

Be it known that I, JOHN REYNOLDS, of the city of Washington, District of Columbia, have originated and designed a new pattern or configuration of a Buggy, having the style, finish, and combination of a cut-under coal-box Jenny Lind, with stationary top, of which the following is a full, clear, and exact description, reference being had to the accompanying drawing, making part of this specification:

Figure 1 is a side view of my buggy.

Letter A is the wheel-house or safety cut-under, with or without horizontal perch, *a*, admitting the insertion of the front wheels when the buggy is driven round a sharp turn. These wheels can be made to revolve on a centre axis, (which is not new,) so as to run through the cut-under, or only half through when the cut-under is made with a horizontal perch, *a*. They then come in contact with it, and are in either case completely removed out of the way in getting in and out of the buggy. B is a light stationary top, consisting of six round pillars, *b b b*, supporting an arched roof, and fastened at *c c c*, to which curtains are attached that can be rolled up or buttoned in the usual way. The fluting, C, runs from the foot-board around the cut-under, and all round the rounded corners of the buggy to the foot-board over a thin iron plate, which binds and strengthens the wood-work of the vehicle substantially.

What I claim as my invention, and desire to secure by Letters Patent, is—

The design or pattern of a cut-under coal-box Jenny Lind buggy, allowing wheels to act as described, with moulded and rounding corners, as herein set forth.

JOHN REYNOLDS.
